UNITED STATES PATENT OFFICE.

EDWIN C. BURT, OF NEW YORK, N. Y.

IMPROVEMENT IN SHOES, &c.

Specification forming part of Letters Patent No. 146,801, dated January 27, 1874; application filed November 24, 1873.

To all whom it may concern:

Be it known that I, EDWIN C. BURT, of the city, county, and State of New York, have invented a new and useful Improvement in the Construction of the Soles of Shoes; and I do hereby declare that the following is a full, clear, and exact description of the same, reference being had to the accompanying drawing forming a part of this specification.

The invention relates to a novel mode of constructing and conjoining the upper, inner, and outer soles of a boot or shoe, as hereinafter fully described, and pointed out in the claim.

Figure 1 is a plan view of top of channeled outsole; Fig. 2, a cross-section of the same, and Fig. 3 a top view of the middle sole of a double-soled boot or shoe.

A represents an outer sole, having the channel *a* located at a short distance from the edge, and beveled upwardly to the top of middle *a'*, which has the full thickness of ordinary soles. When the soles are to be united to the upper,

I am thus enabled to sink the upper B in the channel *a* of outsole A, and cause the insole C to overlap said channel, thereby doing away with the usual projection of upper and of insole, while the middle or wearing part of outsole is preserved in its full thickness. Of course by this construction the upper B is very effectually protected, and rendered more durable, while a closer joint is formed for the exclusion of water and dust.

Having thus described my invention, what I claim as new is—

A boot or shoe having outer sole A of full thickness, except in channel *a*, an upper sunk in said channel, and an insole overlapping the channel, as and for the purpose described.

The above specification of my invention signed by me this 20th of November, 1873.

EDWIN C. BURT.
